Inventor:

Charles T. Raschick.
By Arnold P. Fischbeck

his Attorney.

UNITED STATES PATENT OFFICE.

CHARLES T. RASCHICK, OF ST. PAUL, MINNESOTA.

INDEX.

Application filed April 13, 1921. Serial No. 461,014.

My invention relates to indexes for books and the like and particularly for coupon books and has for its object to provide a construction whereby a number of different leaves within the book may be independently exposed for accessibility in opening the book to the desired pages, said construction being formed by a single simple operation upon the edges of the leaves, which same operation is performed upon all of the leaves thereby greatly reducing the cost of constructing the same.

In carrying out my objects I provide a single die for cutting away a portion of the edge of each leaf of the book, said die being of a width sufficient to expose a number of the index portion of the various leaves at one time. In utilizing this system the cuts are shifted along the various leaves in amounts sufficient to expose certain portions thereof on which are marked the indicia required.

The full objects and advantages of my invention will appear in connection with the detailed description thereof and are particularly pointed out in the claims.

In the drawings, illustrating the application of my invention in one form:—

Fig. 1 is a plan view of a coupon book showing my invention applied thereto.

Fig. 2 is an enlarged end view of the book shown in Fig. 1.

Figs. 3 to 9 inclusive, are plan views of end portions of various leaves in the book shown in Figure 1.

Fig. 10 is a view similar to Fig. 2 showing a slight variation in the form of application of my invention.

In the drawings I have shown an ordinary type of coupon book having a cover 10 and a number of leaves 11 all bound together at one end by wire stitches 12 which, if desired, may be covered by an edging strip 13 of cloth or some other suitable material. The leaves 11 comprise sets of coupons of various denominations which are indicated in the various Figures 3 to 9 inclusive, at 14, 15, 16, 17, 18, 19 and 20. These leaves may be divided into detachable coupons, portions of which are shown in the above figures, which may be provided with numerals designating their values which I have shown ranging from one cent to one dollar. If desired each set of coupons of each denomination may be made of different colored material and if desired other printed matter may be inserted

upon the coupon as becomes necessary to the proper uses of the same.

As clearly shown in Figures 3 to 9 inclusive, the lower edge 21 of each of the coupons is cut to provide an elongated notch 22 which has an edge 23 running parallel to the lower edge 24 of the leaves 11 and which has two side edges 25 and 26 issuing from the edge 24 and meeting the edge 23 of said notch in a rounded corner. From an inspection of the various figures it will be noted that a similar notch 22 is formed on each of the leaves 14 to 19 inclusive, said notches being of the same shape and dimensions but being positioned on the edge of the coupon so that portions of succeeding coupons are exposed to view as indicated at 25, 26, 27, 28, 29 and 30 in Figure 1. In constructing the coupons a single die is employed which cuts the same out as indicated at 22 in all of the leaves. By positioning the die relative to the edge of the coupons which it is to cut or vice versa, the various notches are shifted along the edge of the coupon so as to expose the edges 25, 26, 27, 28, 29 and 30 thereby presenting a portion of each succeeding coupon whereby the same may be engaged by the finger to cause the book to be opened at any required page.

It can be readily understood that by punching a number of coupons with a notch 22 located in the same position and by assembling similarly cut coupons as indicated in Figure 2, that the various types or classes of coupons which may be indicated by their respective denominations may be instantly referred to without turning all of the individual leaves comprising the entire book. It can further be comprehended that any number of coupons or leaves may be inserted having the notches positioned in the same location so that the number of pages comprising each section may be varied at will. From an inspection of Figure 2 it will be seen that the various portions 25 to 30 of the respective leaves 11 gradually step downwardly while at the same time corresponding portions 31 are formed which exist on the underside of the leaves in exactly the same stepped relation to one another as the aforementioned portions. In the drawings, I have shown the last exposed portion 30 occurring in advance of the first under portion 31 so that all of these exposed portions are clearly presented to view by looking

downward upon the coupon book. It will, however, be readily comprehended that where the book is thick enough so that the distance from the point 32 to the point 33 of these exposed edges is sufficient, that the lowermost edge of the coupon may be read from beneath the edge 32 by looking obliquely at the end of the book. If desired the stepping may continue so that 10 additional exposed portions similar to 30 may be provided extending parallel to and below the respective portions 31 thereby increasing the number of indexes to the system. This I have shown in Figure 10 in 15 which a number of upper exposed portions 36 are provided which extend below the portions 37 similar to the portions 31 shown in Figure 2. It will here be noted that an irregular substantially parallel space 38 is 20 provided which extends diagonally downwardly along the edge of the book exposing consecutively portions of different leaves of the book. By running the thumb within the space 38 the same can be stopped upon 25 any of the exposed index portions 29 which occur below the portions 37 so that the index may be made as extensive as desired and still be rendered perfectly serviceable and effective.

29 In the drawings I have shown portions 25 to 30 provided with indicia indicating the denominations of the coupons represented by the same. These indicia run from one cent to one dollar as specified. The top cover 10 35 is preferably formed with a slot therein extending up to the extreme edge 34 of the upper coupon 20 at one end and extending clear across said cover at its other end thus leaving all of the portions 25, 26, 27, 28, 29 40 and 30 and a portion 35 of the upper coupon exposed on which may be placed the respective index mark. Although I have particularly described my invention as applicable to coupon books it can be readily understood 45 that the same may be used for any sort of indexes in conjunction with any form of book or filing system.

The advantages of my invention are manifest. The entire index system can be 50 constructed for a very trivial cost with a single

set of dies by simply altering the relative positioning of the dies and the member on which said dies are adapted to operate as each run of sheets has been completed. The device is extremely convenient in use since 55 the thumb nail can be easily run down between the upper and lower protruding ends of the leaves on the book and stop on the desired index mark after which the leaves can be separated at the desired point. 60

In accordance with the patent statutes I have described the principles of operation of my invention, together with the apparatus which I now consider to represent the best embodiment thereof, but I desire to have 65 it understood that the construction shown is only illustrative and that the invention can be carried out by other means and applied to uses other than those above set forth within the scope of the following 70 claims.

I claim:

1. In combination with a plurality of sets of consecutively arranged members having different indicia thereon, a marginal slot 75 formed along the edges of each of said sets of members, said slots being of the same width and length and being arranged to successively expose portions of the margins of said members, the length of said slots being 80 equal to the length of several of the exposed marginal portions of said members whereby a continuous groove extends diagonally through said members.

2. In combination with a plurality of sets 85 of consecutively arranged members having different indicia thereon, a marginal slot formed along the first set of said members, positioned near one end thereof, similar slots of the same length and depth formed 90 on each of the others of said sets of members, said slots being positioned to successively expose portions of the margins of said sets of members and of a length equal to the combined length of all of the exposed marginal 95 portions whereby a continuous groove extends diagonally through said members.

In testimony whereof I affix my signature.

CHARLES T. RASCHICK.
